UNITED STATES PATENT OFFICE.

ALBERT F. PRESTON, OF LYNN, ASSIGNOR TO THE PRESTON MACHINE COMPANY, OF BOSTON, MASSACHUSETTS.

MACHINE FOR MARKING THE QUARTERS OF BOOTS OR SHOES FOR BUTTONS AND BUTTON-HOLES.

SPECIFICATION forming part of Letters Patent No. 317,416, dated May 5, 1885.

Application filed August 6, 1884. (No model.)

To all whom it may concern:

Be it known that I, ALBERT F. PRESTON, of Lynn, in the county of Essex and State of Massachusetts, have invented certain new and useful Improvements in Machines for Marking the Quarters of Boots and Shoes for the Buttons and Button-Holes, of which the following is a full, clear, and exact description.

This invention relates to a machine for marking the uppers of a boot or shoe where the buttons are to be secured thereto and where the button-holes are to be made therein, so that when the buttons are afterward secured on the quarter and the button-holes made in the button hole piece, and the boot or shoe finished, the buttons and button-holes will be in their true positions relative to each other and to the uppers of the boot or shoe; and the invention consists in the construction and arrangement of parts constituting such a machine, all substantially as hereinafter fully described and shown.

In the accompanying sheets of drawings this invention is illustrated, in Sheet 1, Figure 1 being a plan view; Fig. 2, a longitudinal vertical section on line 2 2, Fig. 1; Fig. 3, a partial side view and partial transverse section on line 3 3, Fig. 1; in Sheet 2, Fig. 4 being a detail plan view below line 4 4, Fig. 2; Fig. 5, a side view and transverse section similar to Fig. 3, with the uppers of a boot or shoe in section and in position for operation thereon by the machine; Fig. 6, a plan view, and Fig. 7 an edge view, of a gage, to be hereinafter referred to.

In the drawings, A represents a frame of iron, or of any suitable material, of U shape, and attached by its lower arm, B, to the under side of a bed or table, C, which bed or table C is supported in any suitable manner.

D is a rod or bar fitting within a socket, a, in the outer end of the upper arm, E, of the U-shaped frame A, and secured therein by a setscrew, b, its lower end, d, extending a short distance below the under side of the arm.

F is a thin strip or plate of metal, preferably of spring-steel, secured by screws e e at its end f to the inside g of the frame, under the arm E, and from thence extending toward and under the lower end, d, of the rod or bar D. This plate F, on its upper surface at its end h,

has an upwardly-projecting pointed pin, l, directly under the center of the rod or bar D.

G is a block, preferably round in cross-section, and fitting within a correspondingly-shaped socket, m, in the bed-plate C, and having on its under side a downwardly-projecting extension, H, of smaller diameter, which fits within a socket, n, in the arm B of the frame, its lower end, r, extending a short distance below said arm. This block, with its extension, can freely move up and down in the sockets m n.

J is a horizontal lever, pivoted at s between two arms, t, of the frame A, its outer end, u, connected by a pitman-rod, K, to any suitable operating foot-treadle. (Not shown in the drawings.) The other end, v, of said lever J, extends to and under the lower end of the spindle H of the block G. Operating the treadle to pull the end u of lever J down will correspondingly raise its other end, v, and thus the block G. On the upper surface of the block G is a pointed pin or projection, w, and located so as to be under the pin l of plate F.

L is a thin strip or plate, preferably of steel, secured by its end x to a block, y, by a setscrew, z, which block is preferably of metal, and is secured to the table C by screws or otherwise. The other end, M, of this plate is free, and lies under the spring-plate F and between it and the block G with its pin w. The plate L has two holes, a², in its end x, which fit over pins b² of block y, by which lateral movement of the free end M of the plate is prevented. The plate also has a screw, d², adapted to screw through the same, having a head, f², and arranged to abut against the block y, so that, by screwing said screw d² in or out, the end M of the plate L can be adjusted as to height from the table C to have it in convenient position for the uppers to be placed in proper position for operation thereon.

In the operation of the machine to mark the uppers of boots and shoes, the two quarters N P, having first been stitched or secured together as usual with their face or front sides outward, and with the button-hole piece Q secured to its quarter, the upper so secured is placed in the machine by inserting the end M of plate L between the two quarters N and P at their end g², and placing the button-hole

- piece Q over the plate F between it and the rod or bar D, its edge bearing against the shoulder h^2 of the gage R on the plate F. When so placed, the treadle is operated to raise the block G so that all parts between it and the rod D are pressed firmly against its lower end, d , causing the pin l of the plate F to indent or mark the face side of the button hole piece Q, and the pin w of the block G to mark the face side of the quarter P. The block G is then allowed to fall, which returns all parts to their normal positions, leaving the upper free to be moved along to mark for the next button-hole and button in a similar manner, and so on until all are marked, when the upper is removed from the machine.

The gage R is secured to the upper side of the plate F by a set-screw, l^2 , which passes through an elongated slot, m^2 , in the same, by which it can be set, as to the distance of its shoulder h^2 from the pin l , to suit the distance the mark should be from the edge of the button-hole piece. The gage R also has a central projection, n^2 , under which the edge of the button-hole piece passes in marking the same.

In order to have the marks equal distances apart, a gage, S, is provided. This gage S consists of a bent metal spring secured by a set-screw, r^2 , by one end, s^2 , to the side of the arm E at its outer end, and extending upward and over the arm E and downward by its other side for its end t^2 , which is pointed to reach nearly to the table, as shown more particularly in section in Fig. 2.

Passing freely through the spring at w^2 is a screw, T, having a head, v^2 , which screws into the side of the arm, and by turning it in or out the point t^2 of the spring will be moved toward or away from the common central vertical line of the markers l w , the spring of the metal of which the gage is made forcing the part t outward as the screw is turned outward, and the distance between its point and the marker will be the distance the button-holes are intended to be apart, and in the use of this gage, it being first set as desired, after the first button-hole is marked, the upper is moved along until the mark made comes under the point t^2 of the gage, when the next button-hole is marked, and this mark moved to and under the gage-point, the third button-hole marked, and so on. Thus all the button-holes will be equal distances from each other.

In marking uppers of boots and shoes having the edge w^2 of the button-hole piece Q scalloped, this gage S is not used, and instead of the gage R a gage, W, (shown in Figs. 6 and 7,) is preferably used. This gage is constructed to be attached to the plate F in a similar manner to the gage R, has the shoulder h^2 , but its projection n^2 has two prongs, y^2 , the distance between their two ends corresponding substantially to the width of the scallop, so that the scallop when placed under it can be adjusted to insure the mark

for the button-hole being in the center thereof, as is obvious.

The object of the plate L between the two quarters, when marking the uppers in this machine, is to serve as a rest or anvil for the pin w to punch against, and to prevent it from marking or in any way injuring the face side of the quarter N, as it might do, especially if the pin should happen to be long enough to pass through or nearly through the two parts. With very thick material for the uppers, and a short pin, w , on the block G, the plate L might be dispensed with, as in such a case the face side of the quarter N might not be marred; but in the use of the machine for general work, to insure the quarter N not being injured, the plate L is necessary and essential.

The plates F and L can extend back from their operating positions in any direction, and can be of any form desired, and secured in any suitable manner, either to the frame or table, as desired. The plate L should, however, be sufficiently narrow, and extend in such a direction for its end M to enter between the quarters, and for the quarters to be moved along and under the bar D, for the proper marking of the parts, according to the sweep or curve of the edges of the quarters, &c.

The marking-pins l and w can be of a length to pass through the thickness of the material being marked, or only sufficient to indent the same, and the pin l can, if deemed necessary, have a square end and punch a hole in the material, and in such case the piece punched out could pass up the central hole, a^3 , of the bar D; but when desired to only mark or indent the material, the end d of the rod D need only have a slight depression; also, the plate L, over the pin w of block G, can have a slight depression on its under side, above the pin w , if deemed necessary. The pin w of block G can be set at one side—that is, either forward or back of the pin l —when desirous of setting the buttons either forward or backward on the piece P, to suit the strain thereon when the boot is buttoned on the person's foot.

The several operating parts can be arranged in any suitable manner—for instance, by reversing them, and operating on the upper side in lieu of from below, although the manner described is satisfactory and practical.

In lieu of either one or both of the pins l and w any suitable marking devices can be used—for instance, small holes can be made in the plates and block, whereby with sufficient power marks or indentations on the uppers could be made. It is preferable to use the pins, as the marks therefrom are more permanent, which is desirous, in view of the after-handling of the upper in the finishing of the boot or shoe.

It is not intended to limit the invention to any particular arrangement of the marking devices, or to any particular manner of securing the quarters together previous to being marked in this machine, as they can be stitched together face to face, in lieu of back to back, as herein shown; nor to the insertion of the

plate L between the two quarters, as it can be placed between the quarter and the button-hole piece, the essential feature of the present invention being the arrangement of devices for 5 marking the uppers of boots and shoes, (for the purposes of this invention,) in combination with a plate inserted between any two of the parts constituting the upper, for the purposes of an anvil or protection of one of said parts 10 from being marred or injured by the marking devices.

The plate F also serves to protect the face of the material it is marking, because of its width and broad surface at the marking-pin.

15 One great advantage of marking uppers of boots and shoes, in a machine constructed like the present invention, is, that when they are being marked they are in a flat and smooth condition, lying closely to one another, which 20 enables a true marking of the places for the buttons and button-holes, and which is accomplished quickly, surely, and in a much more convenient manner than is now done by hand after the stitching of the upper is completed; 25 also, all danger of marring or injuring any of the parts is obviously avoided.

Having thus described my invention, what I claim, and desire to secure by Letters Patent, is—

30 1. In a machine for marking the upper of a boot or shoe where the buttons are to be secured thereto and the button-holes are to be made therein, the combination, with a marker for marking said upper, of a raised plate opposite to the marker, whereby it is adapted to lie between two parts of said upper and on the opposite side of the upper to that whereon the marker makes its impression, substantially as described.

40 2. In a machine for marking the upper of a boot or shoe where the buttons are to be se-

cured thereto and the button-holes are to be made therein, the combination, with marking devices for marking said places having two marking-faces lying in different planes, of a 45 raised plate located between said two marking-faces, whereby it is adapted to lie between two parts of said upper and serve as a base or rest for one or both of said marking-faces, substantially as described. 50

3. The combination, with the bed-plate or table C, having a block, G, arranged to move therein, and provided with a pin, w, a plate, F, provided with a pin, l, of a plate, L, and rod or bar D, substantially as and for the purpose 55 specified.

4. In a machine for marking the upper of a boot or shoe, respectively, where the buttons are to be secured thereto, and the button-holes made therein, a spring-gage, S, having set- 60 screw T, substantially as and for the purpose specified.

5. The combination, with the plate L, secured to the bed-plate C by a set-screw, z, of a screw, d, substantially as and for the purpose spec- 65 ified.

6. The combination, with the plate F, provided with a pin, l, of a gage, R, having shoulder h² and projection n², substantially as and for the purpose specified. 70

7. The combination, with the plate F, provided with a pin, l, of a gage, W, having a shoulder, h², and prongs y², substantially as and for the purpose specified.

In testimony whereof I have hereunto set 75 my hand in the presence of two subscribing witnesses.

ALBERT F. PRESTON.
